Primary Examiner — Mimosa De(74) *Attorney, Agent, or Firm* — Heslin Rothenberg Farley & Mesiti, P.C.(57) **CLAIM**

The ornamental design for a seat, as shown and described.

DESCRIPTION

FIG. 1 is a perspective view of the seat of the present design; FIG. 2 is a front elevation view thereof; FIG. 3 is a rear elevation view thereof; FIG. 4 is a top plan view thereof; FIG. 5 is a bottom plan view thereof; and, FIG. 6 is a right side elevation view thereof, the left side elevation view being a mirror image thereof. The broken lines in the figures depict portions of the seat that form no part of the claimed design.

1 Claim, 6 Drawing Sheets(56)
